CONTINUOUS STERILIZER

Samu-El Ish-Shalom, Brooklyn, N. Y.

Application June 10, 1939, Serial No. 278,513

12 Claims. (Cl. 21—93)

This invention relates to an automatic sterilizer and more particularly to a sterilizer adapted for continuous operation.

The present invention provides a method and an improved means for destroying small organisms and bacteria, and it is primarily intended for the treatment of materials to be used in the manufacture and preparation of cosmetics; but it is also applicable to many other materials, which either for purposes of preservation or as a sanitary precaution or other similar purpose in which it is desirable to destroy or inhibit the growth or development of deleterious germs or any living organism, by utilizing fluid pressure greater than the normal atmospheric pressure.

Materials used in the manufacture of cosmetics which contain bacteria, spores or other living organisms are harmful and tend to discolor the skin and in many cases cause the skin to become thin, wrinkled, dry, inelastic, and subject to uncomfortable irritation.

Therefore, the primary objects of the invention are to provide an improved method and means which shall be adapted for the sterilizing of substances which consist in subjecting such materials and substances to direct air pressure; to provide an improved method whereby the particles of the different materials and substances are fed into the system in mass form but are presented to be sterilized individually and forced into an air stream moving at a high speed and under great compressional energy; to provide an improved method and means whereby materials of different classes may be sterilized and freed of any living organisms which may get eventually into the pores of the skin and cause serious consequences; to provide an improved method whereby the different materials used in the manufacture of cosmetics are not subjected to any discoloration while being sterilized; to keep the sterilizing apparatus at an even temperature and at a temperature most suited for a given material; and to provide an arrangement whereby the material shall be fed continuously at a predetermined rate, so that the sterilizing chamber shall not be overfilled at any time.

It is the further object of this invention to provide an improved method of sterilizing materials used in the manufacture of cosmetics in which definite currents of compressed air are set up continuously in such a manner that those high speed compressed air currents will tend to remove from the inner surface of the walls of the sterilizing chamber materials adhering thereto, thus increasing the efficiency and thoroughness of the sterilizing apparatus.

It is also an object of this invention to provide an improved process in which the sterilizing chamber is arranged so that the air inlets direct the flow of compressed air in the same

direction or in a direction opposite to each other within the sterilizing chamber, so that the currents of materials to be sterilized shall sweep one against the other; to provide an improved apparatus having a plurality of air streams arranged to operate in the same or opposite directions to produce a more efficient sterilizer; and one for carrying out the above processes which will be capable of operating continuously at a high rate of output which shall be of simple construction, easily and quickly assembled and disassembled and therefore easy to maintain in a sanitary condition, and wherein a mixture of materials may be obtained during sterilization.

15 The process and apparatus is not however limited to the use illustratively disclosed therein but may be adapted whenever it is desired to accomplish the same result and bringing about the destruction of bacteria and microorganisms in materials used for other purposes.

In the accompanying drawings constituting a part hereof, in which like reference characters indicate like parts,

Fig. 1 is a front view of an apparatus embodying my invention;

Fig. 2 is a side elevational view thereof, some parts being broken away for clearness;

Fig. 3 is a view similar to Fig. 2, showing still other parts broken away for clearness, and showing the apparatus in a different operative position;

Fig. 4 is a horizontal cross-sectional view taken through the sterilizing chamber;

Fig. 5 is a fragmentary, enlarged, vertical cross-sectional view of the apparatus; and

Fig. 6 is a view similar to Fig. 5, but taken from a different portion of the apparatus.

The apparatus comprises the base 1 having a pair of extensions 2 thereon, provided with ribs 3 or tracks. Mounted on said tracks are sets of wheels 4 mounted for rotation on axles 5 held in bearings 6, which in turn are secured to plate 7 constituting part of sterilizing chamber 8. Through this arrangement, the mixing chamber may be shifted from below the top or cover 26 when desired, to facilitate cleansing of the interior of the mixing chamber. A cover plate 9 removably secured to the base 1 allows access to the interior thereof.

50 A standard 10 secured to the base 1 extends upwardly above chamber 8 terminating in a horizontal overhanging arm 11 within which a vertical screw 12 is mounted. A beveled gear 13 secured to screw 12 meshes with similar gear 14 on horizontal shaft 15 held in bearing 16 and terminating in wheel 17 having handles 18 thereon for manual manipulation of the screw 12. The screw 12 is threaded into horizontal arm 19 having a yoke 20 at one end thereof in sliding engagement with vertical bar 21. The opposite

end has a depending portion 22 terminating in pivot 23. A crank having arms 24 and 25 is mounted on said pivot. Arm 25 is secured to cover 26 of sterilizing chamber 8. Arm 24 has its free end beveled and contacts with similarly beveled portion 27 of block 28 secured to standard 10.

When it is desired to lift the cover 26 from chamber 8, the hand grips 18 are manipulated to turn the wheel 17, thus turning the screw 12 whereupon arm 19 is drawn vertically upward, thus beginning to raise cover 26. By reason of the beveled portion 27 and arm 24, the upward movement of bar 19 causes a tilting of cover 26, as shown more particularly in Fig. 3. This renders the interior surfaces on cover 26 readily accessible for cleaning and other purposes and at the same time renders the interior of sterilizing chamber 8 also readily accessible without interference from the cover 26. An inlet 29 is provided in the base 1 for the introduction of compressed gas such as air or the like. Said inlet is branched at 30 and flexible tubes 31 and 32 are connected thereto, said flexible tubes terminating in pipes 33 and 34 respectively. Each of the latter pipes has branches 35 and 36 communicating respectively with annular portions 37 and 38 of chamber 8, as more particularly shown in Fig. 4. A series of openings 39 in the outer wall of the sterilizing chamber angularly placed, allow the gas entering through openings 35 to pass through the sterilizing chamber in a swirling movement. Similar openings 41 in the inner wall of the sterilizing chamber allow gas from openings 36 to pass into the sterilizing chamber with a similar swirling motion tending to uniformly distribute the currents of gas and material being sterilized.

There is provided a pair of hoppers 42 mounted on blocks 43 having a shaft 44 carrying an agitator 45 within the same and immediately below said hoppers. A gear 46 on shaft 44 meshes with gear 47 which is in turn secured to gear 48 whereby the train of gears may be driven. Shaft 49 rotated by gear 47 has a screw conveyor 50 secured thereto for taking material from hoppers 42 and feeding the same into pipes 51. Said pipes communicate with feed hoppers 52 allowing material to enter chamber 8 at points 53 near the outer circumference of said chamber. At the inner circumference of said chamber there is an exit opening 54 communicating with separator 55 adapted to impart a cyclone action to the mixture leaving the sterilizing chamber and separating the gas from the solid. The solid material drops through opening 56 into removable container 57 whereas the exit gases leave the apparatus through opening 58. Brackets 59 are provided with pivots 60 holding lever arms 61 having weights 62 at one end thereof, the other end being secured to container 57; thereby the weights 62 hold the container 57 in operative position and by the raising of said weights, the said container may be readily removed for emptying the contents thereof.

The driving means for gearing 46-47-48 may be directly connected to the train as shown in Fig. 5, but preferably reduction gearing is provided as shown in Fig. 6. A set of gears 63-64 is provided on sleeve 64a that is loose on shaft 44, the gear 63 meshing with gear 48 and gear 64 meshing with gear 65, the latter being directly connected to drive motor 66. Change speed gearing may be provided at this point.

Sterilizing chamber 8 is kept at a suitable

sterilizing temperature the temperature thereof being largely dependent upon the materials being mixed and sterilized, and for this purpose there is secured to the underside of member 7 5 constituting the bottom of chamber 8 a member 81 forming an additional chamber. A series of electric heaters 68 of any suitable type are secured therein by screws 69 and connection 10 therefrom lead to a source of electrical energy. Generally, heating elements 68 are suitably spaced underneath the entire extent of chamber 8.

The hoppers 42 may be mounted for movement in order to place them in a position so that they will not interfere with the lifting of cover 26 as shown in Fig. 3. For this purpose, there are provided a pair of brackets 71 having at their extreme ends vertical pivot rods 72 on which are mounted bars 73 which in turn are secured to the bases 43 of hoppers 42. Set screws are provided whereby upon the loosening thereof bars 73 may be swung outwardly carrying hoppers 42 with the attached pipes 51 therewith. The cover 26 may be provided with suitable insulating material as for example, a layer of cellular asbestos 74 or the like, such insulating material may be provided about the entire cover, if desired. Briefly, the operation of the improved apparatus is as follows:

The materials to be mixed are delivered into the mixing chamber from the hoppers 42 by the feed mechanism described and more particularly disclosed in Figs. 5 and 6. As the materials are fed into the mixing chamber, air or other gas under pressure is admitted through pipes 35 and 36 into the annular portions 37 and 38 of the mixing chamber. From thence the air passes in streams through the angular openings 39, 41 as indicated by the dotted lines in Fig. 4, to swirl the materials round and round within the chamber 40 and thoroughly mix the same. During the time that this mixing operation is taking place, the temperature within the chamber is maintained at a suitable high level, according to the nature of the materials being mixed and sterilized, so that the materials being mixed are simultaneously heat-sterilized. The mixed and heated materials descend through opening 56 and into the container 57 while the air or gas under pressure leaves the apparatus through opening 58.

Although I have described a single embodiment of the present invention with slight variations therein, the invention is not limited to the details set forth, but should be broadly construed. By the present invention, applicant has provided a new and novel method of continuous operation of a sterilizing device wherein powdered material may be continuously introduced into a chamber, intimately mixed and agitated therein, and a predetermined time elapse, sufficient to give adequate sterilization and then removed from the chamber and separated from the gas used. Based upon these principles many variations in the actual construction both in form and in detail in the apparatus may be made without the principles set forth. Therefore the invention is to be broadly construed and not to be limited except by the character of the claims appended hereto.

What I claim is:

1. An apparatus for continuously sterilizing materials comprising an annular chamber, means for introducing a transporting and agitating stream of gas into and through said chamber,

means for heating said chamber, means for introducing continuously material to be sterilized at one side of said chamber, an exit opening at another side thereof, and a separator for removing and recovering the sterilized material.

2. An apparatus for continuously sterilizing materials comprising an annular chamber, means for introducing a transporting and agitating stream of gas into and through said chamber, said means including a plurality of angularly placed openings along the inner and outer walls of said chamber, means for heating said chamber, means for introducing continuously material to be sterilized at one side of said chamber, an exit opening at another side thereof, and a separator for removing and recovering the sterilized material.

3. An apparatus for continuously sterilizing materials comprising an annular chamber, means for introducing a transporting and agitating stream of gas into and through said chamber, a source of gas supply, flexible tubes for connecting said supply to said means, means for heating said chamber, means for introducing continuously material to be sterilized at one side of said chamber, an exit opening at another side thereof, and a separator for removing and recovering the sterilized material.

4. An apparatus for continuously sterilizing materials comprising an annular chamber, means for introducing a transporting and agitating stream of gas into and through said chamber, means for heating said chamber, means for introducing continuously material to be sterilized at one side of said chamber, an exit opening at another side thereof, and a separator for removing and recovering the sterilized material, said separator being located centrally of said annular chamber.

5. An apparatus for continuously sterilizing materials comprising an annular chamber, means for introducing a transporting and agitating stream of gas into and through said chamber, means for heating said chamber, means for introducing continuously material to be sterilized at one side of said chamber, an exit opening at another side thereof, and a separator for removing and recovering the sterilized material, said separator being located centrally of said annular chamber, and a receptacle for sterilized material below said separator.

6. An apparatus for continuously sterilizing materials comprising an annular chamber, means for introducing a transporting and agitating stream of gas into and through said chamber, means for heating said chamber, means for introducing continuously material to be sterilized at one side of said chamber, an exit opening at another side thereof, and a separator for removing and recovering the sterilized material, a base, a plurality of tracks thereon, said chamber being mounted on wheels, the latter running on said tracks.

7. An apparatus for continuously sterilizing materials comprising an annular chamber, means for introducing a transporting and agitating stream of gas into and through said chamber, means for heating said chamber, a plurality of hoppers above said chamber, means for introducing continuously material to be sterilized at one side of said chamber from said hoppers, an exit opening at another side thereof, and a separator for removing and recovering the sterilized material.

8. An apparatus for continuously sterilizing

materials comprising an annular chamber, means for introducing a transporting and agitating stream of gas into and through said chamber, means for heating said chamber, means for introducing continuously material to be sterilized at one side of said chamber, a movable cover on said chamber to allow access thereto, an exit opening at another side thereof, and a separator for removing and recovering the sterilized material.

9. An apparatus for continuously sterilizing materials comprising an annular chamber, means for introducing a transporting and agitating stream of gas into and through said chamber, means for heating said chamber, means for introducing continuously material to be sterilized at one side of said chamber, an exit opening at another side thereof, and a separator for removing and recovering the sterilized material, a base, a standard rising therefrom and extending above said chamber, a cover on said chamber, cover lifting mechanism secured to said cover and operatively secured to said standard.

10. An apparatus for continuously sterilizing materials comprising an annular chamber, means for introducing a transporting and agitating stream of gas into and through said chamber, means for heating said chamber, means for introducing continuously material to be sterilized at one side of said chamber, an exit opening at another side thereof, and a separator for removing and recovering the sterilized material, a base, a standard rising therefrom and extending above said chamber, a cover on said chamber, cover lifting mechanism secured to said cover and operatively secured to said standard including a pivoted crank, one arm of which is secured, the other arm contacts with said standard, and a screw member secured to said pivot and mounted in said standard.

11. An apparatus for continuously sterilizing materials comprising an annular chamber, means for introducing a transporting and agitating stream of gas into and through said chamber, means for heating said chamber, means for introducing continuously material to be sterilized at one side of said chamber, an exit opening at another side thereof, and a separator for removing and recovering the sterilized material, a base, a standard rising therefrom and extending above said chamber, a cover on said chamber, cover lifting mechanism secured to said cover and operatively secured to said standard including a pivoted crank, one arm of which is secured, the other arm being beveled and contacting with a similarly beveled portion of said standard, and a screw member secured to said pivot and mounted in said standard.

12. An apparatus for continuously sterilizing materials comprising an annular chamber, means for introducing a transporting and agitating stream of gas into and through said chamber, means for heating said chamber, means for introducing continuously material to be sterilized at one side of said chamber, an exit opening at another side thereof, and a separator for removing and recovering the sterilized material, a base, a standard rising therefrom and extending above said chamber, a cover on said chamber, cover lifting mechanism secured to said cover and operatively secured to said standard, said mechanism lifting said cover upwardly and turning the same laterally.
